UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed May 17, 1922. Serial No. 561,603.

To all whom it may concern:

Be it known that I, HAROLD G. WARR, a citizen of the United States, residing at Park Ridge, in the county of Cook and State of Illinois, have invented certain new and useful Improvements in Rail Anchors, of which the following is a specification.

My invention relates to rail anchoring devices adapted to resist the tendency of railroad rails to move longitudinally.

One of the objects of the invention is to provide an improved one piece rail anchor which may be easily applied to or removed from the base flanges of a rail without danger of subjecting the anchor to excessive strains and which will be maintained in its applied position by spring pressure of the anchor.

A specific object of the invention is the provision of a rail anchor having a jaw adapted to be driven into tight engagement with one flange of a rail base and having a body which extends under the rail base and engages the other edge thereof, the body being provided with a portion having greater flexibility than the jaw portion, whereby the flexing of the body of the anchor will relieve the jaw portion of excessive strains during the application of the device to a rail.

A more specific object of the invention is to provide an anchor device that may be formed from a single bar of metal by bending the same to provide a hook shaped jaw adapted to be driven upon one of the base flanges of a rail base and provided at the other end with an offset or shoulder adapted to engage the opposite edge of said rail base; the hook shaped jaw having such configuration that the flexing strains incident to the forcing of the jaw upon the base flange will not be confined to one point of the jaw, such as is common in certain other types of anchors, but on the contrary will be distributed over substantially the entire jaw.

Another object is to provide a rail anchor having novel abutments engaging opposite edges of the rail base that may be formed by an inexpensive operation and to further provide the body of the anchor at a point intermediate its jaws with a portion having greater flexibility than the other parts of the anchor so that the more rigid parts of the anchor will be subjected to a minimum

amount of flexure during the application of the device to a rail.

The invention further consists in such other new and improved constructions relating to rail anchors as will be hereinafter described and claimed for carrying out the above stated objects and such other objects as will appear from the following description.

The invention is illustrated in certain preferred embodiments in the accompanying drawing, wherein like characters of reference designate corresponding parts throughout the several figures thereof and wherein—

Fig. 1 is a front view in elevation of a rail anchor device constructed in accordance with my invention shown applied to the base flange of a rail, the said base flange of the rail being shown in cross section and the approximate distortion of the anchor being indicated by the dotted line configuration of the anchor;

Fig. 2 is a view similar to Fig. 1 showing the position that the anchor assumes during its application to a rail.

Fig. 3 is a plan view of the structure shown in Fig. 1.

Fig. 4 is a front view, in elevation, of a modified form of anchor.

Fig. 5 is a plan view of the structure shown in Fig. 4.

Fig. 6 is a front view in elevation of another modified form of anchor device, and

Fig. 7 is a view in perspective of the anchor device shown in Fig. 6.

Referring first to Figs. 1, 2 and 3 of the drawing, 10 designates the base portion of a railway rail and 11 one of the cross ties on which the rail is supported.

My improved rail anchor, as shown in Figs. 1 to 3 inclusive, is preferably made from a relatively heavy bar of metal having some resiliency, such, for example, as steel, and consists of a body portion 12 formed at one end with a spring jaw 13 for engaging one of the base flanges of the rail, and at the other end with a shoulder 14 adapted to engage with the other edge of the rail base. The spring jaw 13 is formed by bending one end of the body portion 12 to provide a relatively large hook, the end portion of which curves downwardly toward the rail base so that its end only will bear against the upper inclined surface of said rail base. The ex-

treme end of the hook is preferably bent upward, as indicated by the reference numeral 16, so as to provide a flat bearing surface which will bear firmly against the upper surface of the rail base when the anchor is driven transversely of the rail to its applied position. The vertical distance between the bearing surface 16 of the jaw 13 and the upper surface of the body 12 is normally less, when free of the rail, than the thickness of the rail base at the point engaged by the end of the hook when the anchor is in its applied position. The jaw 13, therefore, is subjected to a flexing stress when the anchor is in its applied position. The shoulder 14 at the end of the body, instead of being formed by bending the bar 12 in the manner customary in the manufacture of devices of this character, is preferably offset at 17 with relation to the body 12 of the anchor. By offsetting the end of the bar to provide the shoulder 14, a substantial saving of labor and material is effected, since the offset 17 may be formed by a simple pressing or upsetting operation and less stock is thereby required than would be necessary to form a shoulder of equal height by bending the end of the body.

In order to minimize the flexing of the resilient jaw 13 during its application to a rail, the body portion 12 is bent to provide a downwardly inclined surface 18, the inclined surface providing suitable clearance for the adjacent edge of the rail base when the anchor is in its partially applied position, as shown in Fig. 2. The bend 12^a is, preferably, so disposed with relation to the bearing point of the jaw 13 on the upper surface of the rail base, as to minimize the flexing of the jaw during its application to a rail and at the same time provide sufficient spring pressure to hold the shoulder end 14 of the anchor in its operative position. The application of the anchor to a rail is further facilitated by reducing the thickness of the bar at one end, preferably by pressing so as to increase the flexibility of the body of the anchor. The pressing operation also has another advantage in that the material removed from the reduced portion is swaged into the other portion of the bar. With such construction the thinner portion 20 of the anchor body permits the end of the anchor adjacent the shoulder 14 to flex downwardly, thereby minimizing the angle, designated 21, between the under surface of the rail base and the upper surface of the anchor body, so that the jaw 13 will not be flexed, during the application of the anchor, to any appreciable distance beyond the point that it assumes when in its normal operative position.

In application of the anchor to a rail, the jaw 13 is applied over one edge of the rail base and the anchor is then driven in the

direction of its length across the rail until the shoulder 14 snaps into engagement with the edge 22 of the rail base and the inner surface 19 of the jaw 13 engages with the opposite edge of said base. In Fig. 2, the anchor is shown in a partially applied position, in which position, the offset portion 17, forming the shoulder 14, bears against the undersurface of the rail; this end of the anchor being flexed downwardly at the thin, 75 weaker portion 20. When the anchor is driven home, the jaw 13 is flexed from its normal inoperative position, with respect to the body 12, as indicated in dotted lines in Fig. 1, to its operative position shown in 80 full lines in Fig. 1. When the anchor is in its operative position, the distance between the shoulder 14 and the surface 19 of the jaw is preferably such that they will take a shackle hold on the vertical edges of the 85 rail base, should the anchor, for any cause, be shifted to a slightly diagonal position.

In Figs. 4 and 5, I have shown a modified form of anchor device embodying certain of the features of the device shown in Figs. 90 1, 2 and 3. In this modified construction, the anchor device is made of sheet metal, preferably spring steel, and is formed at one end with a relatively rigid jaw or hook portion 23 which engages both the upper and 95 lower surfaces of the rail base and at the other end with an upstanding lug or shoulder 24 adapted to engage the opposite edge of the rail base. The body portion 25, preferably, decreases in width toward the shoulder 24 so that the portion of the body adjacent the shoulder will be more flexible than the portion of the body adjacent the jaw end of the anchor, whereby the body portion will be flexed on a horizontal axis when 100 the jaw 23 is driven to its rail gripping position. As soon as the shoulder 24 clears the edge of the rail base, it will snap into the position shown in Fig. 4. The lip 26 of the jaw portion is preferably formed with a 105 recess 27 so as to insure a firm contact of the end portion of the lip with the rail base, and the upper edge of the body 25 is recessed, as indicated at 25^a, so as to avoid the shoulder 24 being held out of proper engagement with the edge of the rail base in the event that the under surface of said base is 110 rough and uneven.

In Figs. 6 and 7 I have shown another modification, in which the device is made of 115 sheet metal. This embodiment consists of a flat body portion 28 adapted to extend across a rail base and is formed at one end with two upstanding jaw portions 29—30, having recesses 31 which receive one edge of 120 the rail base. The jaw members 29—30 are adapted to be driven to a tight gripping contact with the upper and lower surfaces 125 of the rail base and the body portion 28 is adapted to function as a spring tongue to 130

5 maintain the device in its applied position. The body portion is preferably bent upwardly toward the rail and its flat upper surface bears against the under surface of the rail base adjacent one edge of the rail, the outer end of the body being formed with an upstanding lip 32 which snaps over the edge of the rail base and engages with the vertical edge thereof. When the anchor is 10 in its applied position one of the upstanding jaw portions 29 or 30, as the case may be, will be in position to bear against an adjacent cross tie.

15 While I have shown my invention in certain specific embodiments, other structural modifications might be made without departure from the spirit of my invention. I, therefore, wish it understood that I contemplate all such modifications coming with 20 in the scope of the appended claims.

I claim:

1. A rail anchor comprising a body portion formed at one end with a resilient jaw for engaging one flange of a rail base and 25 at the other end with a pressed offset portion forming a shoulder for engaging the other flange of said base.

2. A rail anchor comprising a body portion formed at one end with a resilient jaw for engaging one edge of a rail base and 30 having an opening which is normally of less width than the thickness of the rail base at the point engaged by said jaw, and formed at the other end with a pressed offset portion providing a shoulder adapted to engage 35 the other edge of said rail base.

3. A rail anchor comprising a member formed at one end with a spring jaw the vertical dimension of the rail base opening 40 in which, before application of the device to the rail, is less than the corresponding dimension of the rail base at the place engaged thereby so that said jaw has to be spread in application to the rail, and at the other 45 end with an upwardly projecting rail base abutment to bear against the edge face of the rail base at the other side of the rail, the end of said member having the abutment being more flexible than the other end so 50 that it can bend downwardly and then spring back into place as the abutment slides over the under face of the rail base in application of the anchor to the rail to obviate the necessity of excessive spreading of 55 the jaw.

4. A rail anchor comprising a body portion formed with means for engaging opposite edges of a rail base, the means for engaging one of said edges comprising a resilient hook shaped jaw, the end of which extends downwardly toward the rail base and bears against the upper surface thereof with spring pressure to effect a spring grip of the anchor on the rail; the body portion adjacent said hook-shaped jaw being formed

to provide clearance for the edge of the rail base during the application of the anchor to a rail.

5. A rail anchor comprising a member formed at one end with a spring jaw the 70 vertical dimension of the rail base opening in which, before application of the device to the rail, is less than the corresponding dimension of the rail base at the place engaged thereby so that said jaw has to be spread in 75 application to the rail, and at the other end with an upwardly projecting rail base abutment to bear against the edge face of the rail base at the other side of the rail, the intermediate portion of said member being formed 80 to bear continuously against the under side of the rail base, when the device is in operative position thereon, and being more flexible than the portion forming the jaw so that it may bend when the anchor is applied to the 85 rail to obviate the necessity of excessive spreading of the jaw.

6. A rail anchor comprising a body portion formed at one end with a pressed offset portion providing an abutment for engaging 90 one edge of a rail base and at the other end with a spring jaw adapted to be driven over the other edge of said rail base and stressed to grip the upper and lower surfaces of said rail base with spring pressure; said body 95 portion being formed to flex during the application of the anchor to a rail to minimize the flexing of the said jaw.

7. A rail anchor comprising a body portion formed at one end with a hook-shaped jaw having a rail base receiving recess between the extremity of the hook and the body portion of a size insufficient normally to receive the rail base in operative position therein and adapted to be subjected to a 100 flexing stress when applied to a rail, formed at the other end with a shoulder adapted to engage the opposite edge of the rail base, and provided with a portion of maximum 105 flexibility intermediate said jaw and shoulder adapted to be flexed during the application of the device to a rail to relieve said jaw of excessive strains when the anchor is applied to a rail.

8. A rail anchor comprising a body portion formed at one end with a hook-shaped jaw having a rail base receiving recess between the extremity of the hook and the body portion of a size insufficient normally to receive the rail base in operative position 110 therein and adapted to be subjected to a flexing stress when applied to a rail, formed at the other end with a shoulder adapted to engage the opposite edge of the rail base; said body being weakened at a point intermediate 115 said jaw and shoulder to increase its flexibility whereby said jaw is relieved of excessive strains during the application of the device to a rail.

9. A rail anchor comprising a member

4

formed at one end with a spring jaw the vertical dimension of the rail base opening in which, before application of the device to the rail, is less than the corresponding 5 dimension of the rail base at the place engaged thereby so that said jaw has to be spread in application to the rail, and at the other end with an upwardly projecting rail base abutment to bear against the edge face 10 of the rail base at the other side of the rail, the intermediate portion of said member being formed to bear continuously against the under side of the rail base, when the device is in operative position thereon, and the 15 end thereof adjacent said abutment being of smaller cross sectional area than the rest of said member so that it will bend, when the device is applied to the rail to obviate the necessity of excessive spreading of said jaw.

10. A rail anchor comprising a body formed at one end with a jaw portion which engages the upper surface and vertical edge of a rail base and formed at the other end with an abutment for the opposite edge of the rail base; said body being formed to flex 25 downward during the application of the device to a rail.

11. A rail anchor comprising a body formed at one end with a resilient loop providing a jaw portion which engages the upper surface and vertical edge of a rail base and formed at the other end with an abutment for the opposite edge of the rail base; said body decreasing in width toward 30 said abutment and adapted to flex to relieve said jaw of excessive strains during the application of the device to a rail.

35 HAROLD G. WARR.
